UNITED STATES PATENT OFFICE.

THOMAS G. MEINEMA, OF MORTON PARK, ILLINOIS, ASSIGNOR TO EDWARD W. HAMMER, OF CHICAGO, ILLINOIS.

ELECTRIC SWITCH.

SPECIFICATION forming part of Letters Patent No. 669,586, dated March 12, 1901.

Application filed March 1, 1900. Serial No. 6,898. (No model.)

To all whom it may concern:

Be it known that I, THOMAS G. MEINEMA, a citizen of the United States, residing at Morton Park, in the county of Cook and State 5 of Illinois, have invented a certain new and useful Improvement in Electric Switches, of which the following is a specification.

My invention relates to electric switches particularly adapted for motors, and has for 10 its object to provide a new and improved switch, of which the following is a description, reference being had to the accompanying drawings, wherein—

Figure 1 is a diagrammatic view illustrating a device embodying my invention. Fig. 15 2 is a side elevation of the device illustrated in Fig. 1.

Like letters refer to like parts throughout both figures.

As illustrated in the drawings, I have shown 20 my invention as applied to an electric switch for motors. For the purposes of illustration I have shown diagrammatically a simple switch mechanism for regulating electric motors, but it is of course evident that any other suitable switch than that herein shown may be used, and I in no manner limit myself to the form, construction, or arrangement of switch mechanism.

Referring now to Fig. 1, I have shown a 25 switch-arm A, adapted to be moved past the contacts B, with which are associated the several resistance-coils C, adapted to be inserted into the circuit of the motor while starting and controlling the same. The switch-arm A is adapted to be moved in either direction along said contacts, so as to vary the resistance in the armature-circuit in the usual way. The arm A and the several contacts are connected in circuit in any suitable manner.

A suitable retracting device is associated with the arm A and is adapted to move it back to its initial position on the point B' when said arm is released. It is of course evident that 40 any suitable device for this purpose may be used, and in the drawings I have illustrated such retracting device as consisting of the coiled spring A', associated with the arm, so as to retract it in the manner desired. As 45 associated with the arm A is a magnet D, preferably connected in circuit with the field-

magnet coils E of the motor. This magnet is provided with an armature D', movably mounted in proximity to the pole-pieces of the magnet. Connected with this armature D' 55 is an engaging piece D², adapted to engage the arm A or some part associated therewith and hold said arm in certain predetermined positions. The parts are so constructed that when the current ceases to flow through the field-magnet, and hence through the magnet D, the engaging piece D² becomes disengaged from the arm A, and said arm is automatically retracted to its initial position. It is of course 60 evident that the engaging piece D² may be associated with the arm A in any desired manner. As illustrated in the drawings, however, I have shown the arm A as provided with a series of notches A², adapted to be engaged by the engaging piece D². These notches are so 65 positioned that the arm A may be held on any of the contacts B between its initial point B' and its closed position B². The engaging piece D² is preferably either made of resilient material or so connected with the armature D' that it may move along the notches A², associated with the arm A, while the armature D' is held stationary, thus allowing 70 the proper movement of the switch-arm A without moving the armature D' from intimate contact with the metal of the pole-pieces of the magnet D. As illustrated in Fig. 1, the armature D' is pivoted at the point D³, and the engaging piece D² consists of a spring 75 or piece of resilient material suitably connected with said armature.

I have described in detail a particular construction embodying my invention; but it is of course evident that various constructions may be used without departing from the 80 spirit of my invention, and I therefore do not wish to be limited in any manner by the construction shown.

The use and operation of my invention are as follows: In the operation of electric motors, 85 for example, it is customary to start the motor with an external resistance in the armature-circuit and then vary said resistance in the manner desired. When a device such as herein illustrated is used in connection with 90 motors, it insures the return of the arm controlling this resistance to its initial point as 100

soon as the circuit through the field-magnets of the motor is broken or falls below a predetermined amount, thus preventing injury to the motor due to excess of current through the armature. If when my device is used the circuit through the motor is completed, the magnet D attracts its armature D', said armature being moved into contact with the pole-pieces of the magnet. The arm A is now moved past the contacts B, so as to vary the resistance in the armature-circuit of the motor, the engaging piece D² engaging one of the notches A² when the arm A is released and holding said arm either in one of its intermediate positions or in its closed position on the contact B². If, for example, the engaging piece D² were rigid and fixed with relation to the armature D', it will be seen that said armature would be moved out of contact with the pole-pieces of the magnet D each time the engaging piece moved from one notch to another. Since the attractive force of the magnet is at a maximum and is much greater when the armature is in contact with the pole-pieces, it will be seen that under such conditions a much stronger magnet will be necessary to move this armature back in contact with the pole-pieces than is necessary to do the work of holding it in contact therewith. By making the engaging piece D² of resilient material it springs in and out as the arm A is moved, so as to engage the various notches A² without moving the armature D' away from the pole-pieces of the magnet, and hence insures the proper working of the device under all conditions. It will also be seen that this construction by allowing the armature D' to be always in contact with the pole-pieces of the magnet makes it possible to use a much smaller magnet and at the same time obtain better results.

By the construction herein shown, whereby the controlling-arm can be moved without displacing the armature or moving it from contact with the pole-pieces of the magnet, I am enabled to use my device in connection with a series-wound motor. If the armature moved away from the pole-pieces when the controlling-arm is moved, the device could not be commercially used with a series-wound motor because of the counter electromotive force upon the action of the magnet.

I claim—

1. An electric switch, comprising a movable arm, a retracting device for said arm, an elastic engaging device for engaging said arm and holding it in a predetermined position, an electromagnet for controlling said engaging device, said engaging device free at one end and fastened at the other end to the armature of said electromagnet so as to be free to move with relation thereto.

2. An electric switch, comprising a movable arm provided with a retracting device, an electromagnet associated with said arm, an armature movably mounted in proximity to the poles of said electromagnet and adapted to be attracted thereby, a spring part connected with said armature and provided with an engaging end adapted to engage said arm and hold it in a predetermined position while said armature is attracted by the pole-pieces of said magnet.

3. An electric switch, comprising a movable arm provided with a retracting device, a spring engaging piece associated with said arm and having an engaging end adapted to engage it and hold it in a predetermined position, an electromagnet associated with said engaging piece and provided with an armature to which said engaging piece is connected, said armature movably mounted in proximity to the pole-pieces of the magnet and controlling the position of said spring engaging piece so as to bring it into engagement with the arm when the electromagnet is energized.

4. The combination with an electric motor of a magnet contained in the circuit of said motor, a movable arm adapted to control the circuit through the armature of said motor, said arm provided with a suitable retracting device, a spring engaging piece provided with a projecting part adapted to engage said arm while it is being moved in controlling the circuit and hold it in a predetermined position, said spring engaging piece connected with the armature of said magnet, the parts so arranged that the arm can be moved to its predetermined position without moving the armature of said magnet from contact with its opposed pole-pieces.

5. An electric switch, comprising a movable arm provided with a retracting device, an electromagnet associated with said arm, an armature movably mounted in proximity to the poles of said magnet and adapted to be attracted thereby, a spring engaging piece connected with said armature, a series of notches associated with said arm adapted to be engaged by said engaging piece, the parts so arranged that said arm can be moved so that the engaging piece moves from notch to notch without removing the armature from contact with the pole-pieces of the magnet.

THOMAS G. MEINEMA.
